UNITED STATES PATENT OFFICE

153,532

DESIGN FOR A PLASTIC FILM MATERIAL

George F. Leister and Mary L. K. Leister, near Pottstown, Pa., assignors to The Beechwood Company, Incorporated, Stowe, Pa., a corporation of Pennsylvania

Application April 1, 1948, Serial No. 145,484

Term of patent 7 years

(Cl. D92—1)

To all whom it may concern:

Be it known that we, George F. Leister and Mary L. K. Leister, both citizens of the United States, residing near Pottstown, in the county of Montgomery and Commonwealth of Pennsylvania, have invented a new, original, and ornamental Design for a Plastic Film Material, of which the following is a specification, reference being had to the accompanying drawing, forming part thereof.

The figure represents a plan view of a piece of plastic film material, showing one complete unit of our new design. The design unit is outlined by dotted lines on the drawing, and is repeated vertically and horizontally in the drawing, as indicated by the extensions beyond the unit boundaries.

We claim:

The ornamental design for a plastic film material, substantially as shown and described.

GEORGE F. LEISTER.

MARY L. K. LEISTER.
